UNITED STATES PATENT OFFICE

2,363,766

PRESSURE COMPENSATOR FOR
DUPLICATING MACHINES

Robert Alonzo Williams, Chicago, Ill., assignor to
Ditto, Incorporated, Chicago, Ill., a corpora-
tion of West Virginia

Application September 18, 1942, Serial No. 458,782

9 Claims. (Cl. 101—132)

The present invention relates to means for feeding copy sheets and copy sheet assemblies to a duplicating machine and particularly to means for feeding copy sheets to the drum of such a machine into engagement with a hectograph duplicating pad or band on the drum so as to take off copies from a copy ink design formed in reverse on the hectograph surface. A machine of the general type to which I refer is disclosed in the patent to Marchev No. 2,150,744. In my prior application, Patent No. 2,315,175, there is disclosed a feeding means which provides a downwardly converging paper guide chute with a stop plate that normally closes the chute in the period when copy sheets are being fed into position to be automatically dropped when desired to operative contact with the drum. In this prior application a resilient plate is provided as a part of the paper guide chute and it extends below the stop plate. The resilient plate is adapted to press against the opposite wall of the chute with a light pressure to aid in maintaining proper alignment where a copy sheet assembly of the unit strip type (a multiplicity of sheets arranged in overlapped, offset relation so that a portion of each sheet is exposed) is being fed to the duplicating drum.

In machines of this type, employed for system work, copy sheet assemblies of the unit strip type are often used. These assemblies naturally have a substantially greater thickness at their intermediate portions than at the sides. They are also of considerable weight and they vary somewhat in thickness. The resilient plate above referred to is of particular advantage in connection with such assemblies in maintaining alignment of the copy sheets of the assemblies as they are advanced to the drum. However, in my prior application above referred to the operation of the resilient plate is controlled directly by a roller riding on a cam that is affixed to the drum, the roller being connected to the plate by a lever arm that is pivoted to the adjacent side frame. The pressure of the plate under such conditions is variable in response to wear of the roller and in response to thickness of the copy sheet assemblies that are being fed to the drum. It is the principal purpose of the present invention to improve the mounting and operation of the flexible plate whereby to obtain an accurate, uniform pressure control therefor.

The more detailed objects and advantages of the invention will appear more fully from the following description, reference being had to the accompanying drawings wherein a preferred form of the invention is shown.

In the drawings:

Fig. 1 is a fragmentary sectional view taken at right angles to the duplicating drum through a duplicating machine of the type hereinbefore referred to. The line on which Fig. 1 is taken is indicated in connection with Fig. 2;

Fig. 2 is a fragmentary sectional view substantially on the line 2—2 of Fig. 1;

Fig. 3 is a sectional view similar to Fig. 1 but taken on the line 3—3 of Fig. 2;

Fig. 4 is a fragmentary sectional view taken on the line 4—4 of Fig. 2;

Fig. 5 is a fragmentary sectional view taken on the line 5—5 of Fig. 2;

Fig. 6 is a fragmentary sectional view taken on the line 6—6 of Fig. 2;

Fig. 7 is a fragmentary sectional view taken on the line 7—7 of Fig. 1; and

Fig. 8 is a perspective view of a portion of the control machine that is employed for the resilient plate.

Referring now to the several figures of the drawings, in which corresponding parts are indicated by the same reference characters, 10 and 11 indicate side frame members at opposite sides of the machine, suitably supported from the main framework 12 of the machine which is of any approved type. A drum 13 is rotatably supported on the framework by a transversely extending shaft 14, such drum being of segmental form with an opening at one side face portion, the drum being provided with means for holding a gelatin band 15 wrapped thereabout, comprising one or more supporting rollers 16 and reels 17.

Between the frame members 10 and 11, a platen roller 18 is rotatably mounted in position by any suitable means, such as the means shown by said prior Marchev Patent No. 2,150,744, by which means the roller is pressed yieldingly toward the drum so as to have operative pressure relationship with the gelatin band on the drum. A table or tray 19 is mounted in front of the drum at a slightly higher level so as to support a pile of copy sheets or copy sheet assemblies in convenient position for being fed by hand to the sheet guiding and supporting means of the machine for being carried one at a time into impression relationship to the gelatin band.

Adjacent to the rear edge portion of the table 19, a shaft 20 is rotatably mounted between the frame members 10 and 11, upon which shaft two bellcrank levers or brackets 21 are loosely mounted for supporting a paper guide 22 in oblique position, each of the brackets being provided with a roller 23 rotatably mounted thereon in position

to engage horizontally extending portions of the framework as shown in Figs. 1 and 3 for limiting the counterclockwise movement of the brackets in said figures. The paper guide 22 is preferably of the type disclosed by my Patent No. 2,285,135, issued June 2, 1942, and the structure accordingly will not be described in detail. The arrangement is such that copy sheets can readily and easily be placed in position by hand one at a time so as to be supported evenly and smoothly thereon ready for a sliding movement downwardly on the guide when the support for the lower edge of the sheet is removed as hereinafter described.

As is clearly shown in Figs. 1 to 3, inclusive, the paper guide 22 normally stands in such position obliquely as to direct a copy sheet assembly downwardly thereon directly past the rear face of the platen roller 18 into engagement with a margin bar 24 of channel form supported by arms 25 fixedly mounted on a shaft 26 journaled between the frame members 10 and 11. The arms 25 extend forwardly beyond the shaft 26 into position to engage a transversely extending bar 27 fixedly mounted in position between the frame members 10 and 11, said arms being provided with cushions 28 in the form of rubber blocks. A coiled spring 29 on the shaft 26 normally holds the shaft 26 turned to the limit of its motion in clockwise direction in Fig. 3 for holding the margin bar 24 yieldingly in raised position directly below the platen roller 18, as shown in Fig. 3. On its outer end, the shaft 26 is provided with an arm 30 having a roller 31 rotatably mounted thereon in position to engage a cam 32 carried around with the drum. When the cam 32 engages the roller 31 as shown in Fig. 1, the continued rotation of the drum and cam causes the shaft 26 to rotate in counterclockwise direction in said figure so as quickly to move the margin bar 24 downwardly and forwardly from the position of the bar in said Fig. 1 to the position as shown in dotted lines in Fig. 3, the margin bar being held in this way out of contact with the gelatin band 15 on the drum.

For directing a copy sheet assembly into engagement with the margin bar 24 as shown in Fig. 3, a guide plate 33 is provided, mounted rigidly in position in front of the lowermost plate portion 34 of the paper guide structure 22 in downwardly convergent position with respect thereto so as to direct the assembly into close proximity to the rear face portion of the platen roller 18. At its intermediate portion, the plate 33 is cut out and bent forwardly to provide a flange 35 and so as to provide an opening in which a stop plate 36 is adapted to operate, such plate 36 being pivotally mounted between the side frames 10 and 11 by a shaft 37 rotatably mounted in front of the plate 33, as is best shown in Fig. 3. In this arrangement, the lower edge portion of the plate is in the form of a bar extending across adjacent to the face of the platen roller 18. A lever arm and light spring arrangement is provided, as shown in Figs. 1 and 6, adapted normally to hold the plate 36 in raised position (see Fig. 3) adjacent to the lower edge of the plate 34 of the paper guide so as to support on edge a copy sheet assembly resting on said plate 36 and said paper guide. The lever arm just referred to is indicated at 38 and is keyed to the shaft 37 which in turn is journaled in the frame 10. The lever arm 38 lies outside of the frame 10. A cam arm 39 is journaled on the shaft 37 just outside the lever arm 38 (see Figs. 6 and 7). The lever arm 38 is connected to the cam arm 39 by a spring 40 that is hooked

into an aperture 41 in the end of the lever arm 38. The other end of the spring 40 is secured to a pin 42 on the cam arm 39. The cam arm 39 has a cam roller 43 at its free end which rides on a cam 43a that is fixed to the drum. The cam arm also has a stop plate 44 fastened thereon. This stop plate is adapted to engage the lower surface of a boss 45 on the side frame 10 when the stop plate 36 is in raised position. There is a pin 42a on the cam arm 39 against which the lever arm 38 is yieldingly held by the spring 40. Thus it is possible for the lever arm 38 to swing in a counterclockwise direction with respect to the cam arm 39 so that if the cam arm is released by its cam before a sheet clears the stop plate 36 the plate will not be pressed against the sheet with sufficient force to damage it. The arrangement is such with respect to the adjacent parts that an operator can quickly and easily place a copy sheet assembly in position on the plate 36 so as to be supported evenly and smoothly thereby ready for a downward movement along the paper guide promptly when the plate 36 is swung downwardly out of supporting position.

Additional means is provided for assisting in the control of the movement of a copy sheet assembly to the drum. This means comprises a thin resilient pressure plate 46 which has its top edge fixed to a stiff angle bar 47. The angle bar 47 is secured at its opposite ends to two supporting arms 48 which are duplicates, except that one is a right-hand and the other is a left-hand arm. These arms are fixed on the shaft 20 which in turn is journaled in the side frames 10 and 11. An arm 49 is fixed to the shaft 20 outside of the frame 10. This arm is forked as illustrated in Figs. 7 and 8, one arm 50 being laterally offset and extending at substantially right angles to the other arm 51. The arm 51 has a cam lever 52 pivoted thereto by means of a bolt 53. Intermediate the bolt 53 and the branching of the arm 50, the arm 51 is provided with a slot 54 extending transversely thereof and curved about the bolt 53 as an axis. A bolt 55 passes through the slot 54 and through an aperture provided in the end of the lever 52 that overlaps the slot 54. A nut 56 is threaded onto the bolt 55. The bolt 55 extends a substantial distance beyond the nut 56 and is connected by means of a spring 57 to the free end of the arm 50. This spring is under tension so that it tends to draw the lever 52 toward the free end of the arm 50. The other end of the lever 52 carries a cam roller 58 which is adapted to engage a cam 59 fixed to the drum 13.

The arms 48 are limited in the degree to which they can turn in response to turning of the shaft 20 by means of the arms 49 and 52 when the roller 58 engages the cam 59. The limiting means comprises two stop brackets 60 and 61 (see Figs. 3 to 5, inclusive) which are mounted on the side frames 10 and 11, respectively.

The brackets 60 and 61 are essentially the same so a description of one is believed to be sufficient. Each bracket carries an adjustable stop pin 62 which is threaded into the bracket and which is provided with an enlarged head 63 carrying the bumper 64 of resilient material such as rubber, neoprene and the like that will yield slightly. A lock nut 65 is provided for holding the stop pin 62 in adjusted position. When a machine is set up for a particular type of work it is only necessary to set the stop pins to thereafter positively control the advance of the plate 46 toward the opposite guide plate 33.

The lever arms 48 are normally yieldingly

urged to a position withdrawing the plate 46 from contact with the other guide plate 33 by means of two springs 66 which are attached to the arms at one end and which are attached at the other end to two pins 67 that are provided on the side frames 10 and 11. In order to limit the movement of the arms 48 in response to the pull of the springs 66 I provide on each of the arms an adjustable stop pin 68 which will engage a boss 69 provided on each of the side frames 10 and 11 and supporting the opposite ends of a cross bar 70. A lock nut 71 is provided for locking the stops 68 in position.

The operation of the device is generally the same as that described in my prior application but in order that the advantages of the present invention will be more readily apparent I will describe the operation and the effect of the improvements. In the original adjustment of the machine, before beginning to make copies, the stops 62 are set to enable the arms 48 to carry the plate 46 toward the plate 33 sufficiently to obtain the proper pressure agains a sheet assembly that is being advanced to the drum for duplication purposes. The stops 68 are also adjusted so as to provide ample clearance to permit the copy sheet assembly to pass between the lower edges of the plates 33 and 46. In making copies the operator initially places a copy sheet assembly in position against the guide 22 and allows it to drop between the plates 33 and 34 upon the stop plate 36. The stop plate 36 at this time is in the dotted line position shown in Fig. 3 and the stop member 44 is in engagement with the bottom of the boss surface 45, the roller 43 being in the depressed portion of the cam 43a. As the drum rotates, the roller 43 moves along the cam 43a until it reaches the portion of larger diameter. At this point the roller 43 is moved outwardly and causes the arm 39 to swing in a counterclockwise direction (see Fig. 6) to thus move the plate 36 out of the way and allow the copy sheet assembly to drop down into the margin bar trough 24. As the drum continues to rotate, the cam roller 58 strikes the cam 59 and the lever 52 is moved outwardly, causing the arm 49 to turn about its axis, thereby rotating the shaft 20. The shaft 20 carries the arms 48 which in turn carry the plate 46. As the shaft 20 turns, the arms 48 will be made to strike the stop pins 62 thus limiting the advance of the plate 46 toward the plate 33 to the amount originally set as being necessary to give the proper grip on the copy sheets. The roller 58 will not have reached the high point of the cam 59 when the stop pins 62 stop the arms 48. However, the lever 52 may continue to turn about its pivot 53 against the tension of the spring 51 until the roller 58 does reach the high point of the cam without in any way changing the position of the plate 46. After the plate 46 has moved into engagement with the copy sheet assembly, the roller 31 engages the cam 32 to move the margin bar 24 from the full line position shown in Fig. 3 to the dotted line position and the gelatin band 15 on the drum advances into engagement with the copy sheet assembly. The platen roller 18 presses the copy sheet assembly against the gelatin band on the drum and the assembly is drawn from between the guide plates 46 and 33 as the drum continues to rotate. The plate 46 acts to keep the several sheets of the copy sheet assembly properly aligned without exerting enough force on them to impede their advance.

It will be evident from the foregoing descrip-

tion of the operation that the only adjustment necessary to position the plate 46 for different copy sheet assemblies is the adjustment of the stops 62. There is ample play provided by the yielding connection between the lever 52 and the arm 49 to take care of any variations encountered. Also, if the roller 58 becomes worn or reduced in diameter in operation there will still be sufficient pressure exerted to move the arms 48 against the stops 62.

This apparatus has the advantage also that in the initial laying of the master copy on the hectograph pad the plate 46 may be set to bear so lightly as to not mar the master sheet that is applied against the hectograph pad. A positive stop 62 is thus provided for the plate 46, which stop is independent of the connections between the arms 48 and the cam roller 58 and cam 59. In the making of copies the adjustments must be quite close to enable one to feed the master copy to the drum without marring its surface, and to thereafter feed copy sheet assemblies to the drum and hold them in proper relation. The present apparatus has been found to give the necessary nicety of adjustment without danger of getting out of order in use.

While there have been shown and described certain embodiments of the invention, it is to be understood that it is capable of many modifications. Changes, therefore, may be made without departing from the scope of the invention as described in the appended claims, in which it is the intention to claim all novelty inherent in the invention as broadly as possible, in view of the prior art.

I claim:

1. In a duplicating machine, the combination of a drum rotatably mounted on a horizontal axis and having a recess in its peripheral surface, a platen roller rotatably mounted in position to press on said drum, an obliquely positioned paper guide along which copy sheet assemblies are adapted to move downwardly one at a time toward said platen roller, a bar extending across adjacent to the face of said roller, means comprising a thin resilient plate movably mounted in position for pressing a copy sheet assembly lightly against said bar and adapted to be flexed readily for applying pressure effectively on different portions of the assembly of different thickness, and adjustable means for limiting the movement of said resilient plate toward said bar for making the mechanism effective with assemblies of different maximum thickness.

2. In a duplicating machine, the combination of a drum rotatably mounted on a horizontal axis and having a recess in its peripheral surface, a platen roller rotatably mounted in position to press on said drum, an obliquely positioned paper guide along which copy sheet assemblies are adapted to move downwardly one at a time toward said platen roller, a plate rigidly mounted in downwardly convergent position with respect to said paper guide in front of the guide and cut out intermediately so as to leave its lower edge portion in the form of a bar positioned closely adjacent to the face of the platen roller, a thin resilient plate movably mounted in position for pressing a copy sheet assembly lightly against said bar and adapted to be flexed readily for applying pressure effectively on different portions of the assembly of different thickness, means for moving said resilient plate toward said bar, and adjustable means for limiting the movement of said resilient plate toward

said bar for providing a predetermined clearance between the resilient plate and the bar so as to prevent the application of excessive pressure on said resilient plate.

3. In a duplicating machine, the combination of a drum rotatably mounted on a horizontal axis and having a recess in its peripheral surface, a platen roller rotatably mounted in position to press on said drum, an obliquely positioned paper guide along which copy sheet assemblies are adapted to move downwardly one at a time toward said platen roller, a plate rigidly mounted in downwardly convergent position with respect to said paper guide in front of the guide and cut out intermediately so as to leave its lower edge portion in the form of a bar positioned closely adjacent to the face of the platen roller, a thin resilient plate movably mounted in position for pressing a copy sheet assembly lightly against said bar and adapted to be flexed readily for applying pressure effectively on different portions of the assembly of different thickness, adjustable means for limiting the movement of said resilient plate toward said bar for providing a predetermined clearance between the resilient plate and the bar so as to prevent the application of excessive pressure on said resilient plate, and means for moving said resilient plate toward said bar and comprising an actuating member yieldingly mounted with respect to said resilient plate so as to permit the actuating member to move without corresponding movement of the resilient plate.

4. In a duplicating machine, the combination of a drum rotatably mounted on a horizontal axis and having a recess in its peripheral surface, a platen roller rotatably mounted in position to press on said drum, an obliquely positioned paper guide along which copy sheet assemblies are adapted to move downwardly one at a time toward said platen roller, a bar extending across adjacent to the face of said roller, arms swingingly mounted at opposite sides of the machine and rigidly connected together so as to swing in unison, a thin resilient plate mounted between said arms and extending transversely beyond the arms in position to swing toward and from said bar for pressing a copy sheet assembly lightly against the bar, said plate being bendable transversely and longitudinally and adapted to be flexed readily so as to apply pressure effectively on different portions of the assembly of different thickness, a third arm connected with said first-named arms for moving said resilient plate toward and from said bar, a fourth arm pivotally connected with said third arm so as to have a limited swinging movement with respect thereto, means for giving said fourth arm a swinging movement in the direction for carrying said resilient plate toward said bar, and yielding means tending to move said fourth arm to the limit of its motion with respect to said third arm for carrying said resilient plate toward said bar but adapted to yield for permitting the resilient plate to move in the direction away from the bar.

5. In a duplicating machine, the combination of a drum rotatably mounted on a horizontal axis and having a recess in its peripheral surface, a platen roller rotatably mounted in position to press on said drum, an obliquely positioned paper guide along which copy sheet assemblies are adapted to move downwardly one at a time toward said platen roller, a bar extending across adjacent to the face of said roller, arms swing-

ingly mounted at opposite sides of the machine and rigidly connected together so as to swing in unison, a thin resilient plate mounted between said arms and extending transversely beyond the arms in position to swing toward and from said bar for pressing a copy sheet assembly lightly against the bar, said plate being bendable transversely and longitudinally and adapted to be flexed readily so as to apply pressure effectively on different portions of the assembly of different thickness, yielding means tending to swing said arms in the direction for carrying said resilient plate away from said bar, adjustable stop means for limiting the movement of said arms in both directions for controlling the movement of said resilient plate toward and from said bar, a third arm connected with said first-named arms for moving said resilient plate toward and from said bar, a fourth arm pivotally connected with said third arm so as to have a limited swinging movement with respect thereto, means for giving said fourth arm a swinging movement in the direction for carrying said resilient plate toward said bar, and other yielding means tending to move said fourth arm to the limit of its motion with respect to said third arm for carrying said resilient plate toward said bar but adapted to yield for permitting the resilient plate to move in the direction away from the bar independently of any swinging movement of said fourth arm.

6. In a duplicating machine, the combination of a drum, a platen roller rotatably mounted in position to press on said drum, a bar adjacent to said platen roller, and means to guide a sheet assembly past said bar to the drum and platen roller, including a plate movably mounted to move toward and away from the bar for pressing sheets lightly against said bar, and means for moving said plate toward said bar comprising an actuating member and a yielding connection between the actuating member and the plate providing limited movement of the actuating member in a direction to urge the plate toward the bar without corresponding movement of the plate toward the bar.

7. In a duplicating machine, the combination of a drum, a platen roller rotatably mounted in position to press on said drum, a bar adjacent to said platen roller, and means to guide a sheet assembly past said bar to the drum and platen roller, including a plate movably mounted to move toward and away from the bar for pressing sheets lightly against said bar, and means for moving said plate toward said bar comprising an actuating member and a yielding connection between the actuating member and the plate providing limited movement of the actuating member in a direction to urge the plate toward the bar without corresponding movement of the plate toward the bar, and adjustable stop means limiting the approach of the plate to the bar.

8. In a duplicating machine, the combination of a drum, a platen roller rotatably mounted in position to press on said drum, a bar adjacent to said platen roller, and means to guide a sheet assembly past said bar to the drum and platen roller, including arms swingingly mounted at opposite sides of the machine and rigidly connected together so as to swing in unison, a thin resilient plate mounted between said arms and extending transversely beyond the arms in position to swing toward and from said bar for pressing a copy sheet assembly lightly against the bar, said plate being bendable transversely and longitudinally and adapted to be flexed readily

so as to apply pressure effectively on different portions of the assembly of different thickness, a third arm connected with said first-named arms for moving said resilient plate toward and from said bar, a fourth arm pivotally connected with said third arm so as to have a limited swinging movement with respect thereto, means for giving said fourth arm a swinging movement in the direction for carrying said resilient plate toward said bar, and yielding means tending to move said fourth arm to the limit of its motion with respect to said third arm for carrying said resilient plate toward said bar but adapted to yield for permitting the resilient plate to move in the direction away from the bar.

9. In a duplicating machine, the combination of a drum, a platen roller rotatably mounted in position to press on said drum, a bar adjacent to said platen roller, and means to guide a sheet

assembly past said bar to the drum and platen roller, including a thin resilient plate movably mounted in position for pressing a copy sheet assembly lightly against said bar and adapted to be flexed readily for applying pressure effectively on different portions of the assembly of different thickness, adjustable means for limiting the movement of said resilient plate toward said bar for providing a predetermined clearance between the resilient plate and the bar so as to prevent the application of excessive pressure on said resilient plate, and means for moving said resilient plate toward said bar and comprising an actuating member yieldingly mounted with respect to said resilient plate so as to permit the actuating member to move without corresponding movement of the resilient plate.

ROBERT ALONZO WILLIAMS.
